PAPER HANGER'S GAUGE

Charlie C. Mitchell, Pasadena, Calif.

Application October 24, 1933, Serial No. 694,983

2 Claims. (Cl. 33—108)

This invention relates to paper hangers' equipment and more particularly to a gauge for properly positioning the straightedge on the paper so that the blank margin along each edge thereof may be removed.

In preparing wall paper before it is applied to the wall it is necessary to trim or remove a portion along the edges. This is done by placing a straightedge thereon, then cutting the strip with a suitable cutter.

However if the straightedge is not positioned parallel with the edge of the folded strip, the abutting edges of the strips will not match properly when they are applied to the wall.

It is therefore the object of the present invention to provide a straightedge and gauge for the same whereby it may be properly positioned in parallel relation to a strip of wall paper.

Other objects and advantages will be apparent from the following description, reference being had to the accompanying drawing, in which:

Fig. 1 is a top plan view of a table or work bench and a strip of wall paper (that has been folded) together with the improved gauge in applied position thereon.

Fig. 2 is an enlarged fragmentary top plan view of the gauge.

Fig. 3 is a section taken on line 3—3 of Fig. 2.

Fig. 4 is a longitudinal section taken on line 4—4 of Fig. 2.

Fig. 5 is a cross section taken on line 5—5 of Fig. 4.

Referring more specifically to the drawing, 10 designates a straightedge of usual form employed in trimming a strip of wall paper, i. e. to remove the surplus alongside of each edge thereof prior to applying the strip to the wall.

Mounted in bearings 12 secured to the straightedge and disposed in parallel relation to its cutting edge 13 is a shaft 14 and slidably mounted on the shaft is a pair of measuring devices generally designated 16. The devices 16 coact with or operate in conjunction with the straightedge so that its cutting edge may be located in a position parallel with and at a proper distance from the edge of the strip of paper in order that the blank portion or margin may be removed therefrom, the devices being constructed as follows.

Each device 16 consists of a sleeve or collar 17 that is secured to or formed integral with an arm or extension 18 that is disposed at right angles to the shaft and projects over the edge 13 of the straightedge.

Arm 18 is in the form of a hollow body substantially square shape in cross section as shown in

Fig. 5 and adjustably mounted in said body is a pair of blocks designated at 20 and 21 to which are secured pointers 22 and 23 respectively.

The pointers 22 and 23 are in the form of flat sheet metal plates and are secured to the under side of the blocks by tongues 24 that extend through a slot 25 formed in the bottom wall of the arm, it being noted that pointer 22 is of slightly greater width than the pointer 23.

Block 21 is threaded on a screw 26 that is journaled in an opening 27 formed in the outer end wall 28 of the arm, the screw being provided with a handle or knob 29 for turning the same.

Threaded on a stud 30 secured to block 20 is a nut 31 for retaining said block in adjusted position in relation to the edge 13 of the straightedge. The stud extends through a slot 32 formed in the upper wall of the arm.

Formed on the inner side face of the arm of each device 16 is a scale 33 by which the pointers 20 may be adjusted to correspond to a given distance, i. e. the width of the margin M to be removed from the strip of wall paper indicated at P.

Formed in shaft 14 is a groove or key way 34 that receives tongues 35 which are secured to the sleeves 17, the tongues and groove being provided in order that the devices 16 will turn in unison.

In preparing the improved scale for use the blank portions or margins extending along the edges of the strip of wall paper indicated at P are first measured to determine their width.

If both margins prove to be of the same width pointers 22 only are employed and are adjusted on the arms 18 in relation to the cutting edge 13 a distance equal the measurement taken (reference being had to the scales 33). The thumb nuts 31 are then tightened to hold the pointers in place. On the other hand should the margins be of unequal width pointers 22 are adjusted to correspond to the narrowest and pointers 23 to the widest margin on the strip. After making the above adjustments the gauge is ready for use.

Assuming both margins are equal and that the pointers 22 have been accordingly adjusted as above referred to, the straightedge is placed on the folded strip with the pointers 22 engaging the edge of the same as shown in Fig. 1.

When thus positioned the cutting edge 13 will be in a plane parallel with edge of the strip and at a distance therefrom equal to the width of the margin to be removed.

The arms carrying the pointers are then turned back as shown in dotted lines in Fig. 1 55

in order that the cutting edge will be unobstructed.

The margins on each edge of the strip may then be successively removed with a usual cutter 5 employed for such purposes.

Thereafter the margins may be removed from additional strips cut from the roll of wall paper without the necessity of measuring the same or locating the straightedge thereon with a rule.

10 The above described operation may be equally as well carried out with strips having margins of unequal width. In such instances the pointers 22 are utilized to locate the straightedge for the narrowest while the pointers 23 are utilized to 15 locate it for the widest margin.

From the foregoing it will be apparent that the straightedge of the gauge may be easily and quickly located to properly position it on strips cut from a roll of wall paper for removal of the 20 blank margin thereon without the use of rules or the like.

I claim:

1. A gauge of the character described comprising in combination a straightedge, a rock

shaft disposed lengthwise of and mounted on said straightedge, a pair of arms slidably mounted on said shaft, a pair of blocks slidably mounted in each of said arms, pointers secured to said blocks, and means for adjusting said blocks whereby the pointers thereon may be adjusted in relation to the edge of said straightedge. 5

2. A gauge of the character described comprising in combination a straightedge, a rock shaft disposed lengthwise of and journalled in a bearing mounted on said straightedge adjacent each end thereof, a pair of arms slidably mounted on said shaft, a pair of blocks slidably mounted in each of said arms, pointers secured to said blocks, screws threadedly engaging one pair of said 15 blocks and extending through openings in the other pair of blocks for adjusting the said one pair of blocks on said arms, studs secured to the other pair of blocks and projecting through slots formed in said arms, and nuts threaded on said 20 studs for adjusting the latter pair of blocks on said arms for the purpose set forth.

CHARLIE C. MITCHELL.
